UNITED STATES PATENT OFFICE.

JULES HAUVENTTE-MICHELIN, OF NEW BRUNSWICK, NEW JERSEY.

DESIGN FOR AN AUTOMOBILE TIRE.

Application filed February 6, 1924. Serial No. 8,552. Term of patent 14 years.

To all whom it may concern:

Be it known that I, JULES HAUVENTTE-MICHELIN, a citizen of the United States, residing at New Brunswick, in the county of Middlesex and State of New Jersey, have invented a new, original, and ornamental Design for Automobile Tires, of which the following is a specification, reference being had to the accompanying drawings, forming a part thereof.

Figure 1 is a plan view of the tire tread, and

Figure 2 is a section on the line 2—2 of Figure 1.

I claim:

The ornamental design for an automobile tire as shown.

In testimony whereof I affix my signature.

JULES HAUVENTTE-MICHELIN.
